UNITED STATES PATENT OFFICE.

ANDREW SMITH, OF SAN MATEO, CALIFORNIA.

WELL-TUBING.

No. 830,184.

Specification of Letters Patent.

Patented Sept. 4, 1906.

Application filed December 6, 1905. Serial No. 290,554.

To all whom it may concern:

Be it known that I, ANDREW SMITH, a citizen of the United States of America, residing at San Mateo, county of San Mateo and State of California, have invented certain new and useful Improvements in Well-Tubing; and I hereby declare the following to be a full, clear, and exact description of the same, reference being had to the accompanying drawings, forming a part of this specification.

This invention relates to certain improvements in well-tubing, commonly called "well-casing" and to double tubes, one inserted within the other, leaving a narrow annulus between and perforations outward and inward through the walls communicating therewith, as hereinafter particularly described, and illustrated by drawings that form a part of this specification.

My improvements consist in outer and inner tubes, each having clean punched perforations to admit water, the perforations through the inner tube being punched outward and those in the outer tube punched inward, so that protuberances produced by punching will project into the annulus between the tubes, leaving both the exterior and interior of the completed tubes smooth and free from obstruction, also permitting water-inlets of uniform and definite size.

The objects of my invention are to attain smooth surfaces on the outside and inside of the tubes; to permit perforations large enough for clean punching as distinguished from slitting; to permit the whole surface of the tubes, including the perforations therein, to be coated with non-corrosive metal; to determine the area of the inlets for water and make them uniform; also, to provide a construction that will permit cleaning or repairing the water-inlet ways from the inside and top of the well.

Referring to the drawings, Figure I is a transverse broken section from a double well-tube, showing the manner of perforating the same; Fig. II, a front view of a partial vertical section in a plane opposite to Fig. I; Fig. III, a side view of some sections of well-tubing drawn to a reduced scale and made according to my invention, and Fig. IV shows a manner of holding the outer and inner tubes concentric.

Impediments met with in tube-wells are to provide interstices or perforations of uniform size, for the infiltration of water small enough to exclude coarse sand and gravel,

clearing such perforations when they become clogged or corroded, also the derangement and closing of the perforations on the outside or inside of the tubes when the latter are forced down. When such perforations are narrow slits, as in common practice, the bur raised by the piercing implements is thin, jagged, and liable to both derangement and corrosion, because the operation of piercing is performed after the tubing is coated or galvanized, leaving the surfaces of the slits or perforations unprotected. There is also the impediment of a specific and limited area for the inlet-ways for water and the difficulty of in any manner clearing such inlet-ways when they become clogged. To avoid these impediments, I employ means now to be described by the aid of the drawings.

The tube or casing is made double, as seen in Fig. I, both the outer tube 1 and the inner tube 2 being perforated at regular intervals, not by slits, but with clean punched holes 3, of such width as to prevent clogging. These holes 3 are staggered in respect to the outer and inner tubes 1 and 2, as indicated in Fig. II, and the limit of area required to exclude solids is attained by the distance 4 between these orifices and the opposite walls 5 and 6 of the casing or, in effect, by the width of the annular space 7 between the tubes.

The space 7 is made of a width to suit the protuberances 8 caused by punching and to suit the character of the formation in which a well is sunk, also to suit for oil-wells or land-drains, to which my invention is equally adapted, being made larger for gravel and narrower for sand or other fine material. This space 7 is modified by the relative diameter of the tubes 1 and 2, and these may be held concentric by bands of metal, as at 11 in Fig. II, or strips disposed lengthwise between the tubes, but preferably indented protuberances, as shown in Fig. IV, raised by a separate non-pervious punch at the same time the perforations 3 are made.

In preparing the tubes the perforations 3 and indentations 8 are punched or formed before the sheets or tubes are coated or galvanized, so that the whole surface is protected from corrosion, the perforations being large enough to permit the melted coating-metal to flow through and drain out.

The perforations 3 when not relied upon to screen or strain the entering water, as in Fig. IV, can be made of considerable width, preferably an eighth of an inch or more than

this, and as the entering water or oil can flow each way from these perforations 3, so the screening area will thus be doubled and admit twice as much as would pass through an equal number of radial slits acting as screens. In case of the inlet-ways 3 becoming clogged a pneumatic hammer or other device to deliver blows from the inside can be lowered in the well and the inlet-passages be opened by concussion.

It will be understood that while my invention is described especially as well-tubing, its general object is to extract or drain water from gravel, sand, or earth and is applicable to various purposes where this function is required.

Having thus explained the nature and objects of my invention, what I claim as new, and desire to secure by Letters Patent, is—
20 1. In well-tubing, double walls consisting of an outer and inner tube, the outer tube having perforations punched inwardly and the inner tube having perforations punched outwardly, leaving the exterior and interior 25 of the completed tube free from protuberances or obstruction, substantially as specified.

2. In well-tubing, a double-walled tube, said walls having perforations punched 30 therein, arranged in staggered positions relatively, leaving an annular space between the walls, into which space the protuberances made by punching project inwardly from the outer wall and outwardly from the inner 35 wall, and imperforate protuberances on one of said walls projecting into said annular space to gage the clearance of the water-inlet ways, substantially as specified.

outer wall and outwardly from the inner wall, and means for holding said outer and 35 inner walls concentric, substantially as specified.

3. In well-tubing, two concentric walls enclosing an annular space, said walls having perforations punched therein arranged in 40 staggered positions relatively, the protuberances made by punching projecting inwardly from the outer wall into said annular space and outwardly from the inner wall into said space, but not contacting the opposite wall, 45 thereby leaving a screening-space between the mouths of the perforations and said opposite wall, substantially as specified.

4. In well-tubing, a double-walled tube, said walls having perforations punched 50 therein, arranged in staggered positions relatively, leaving an annular space between the walls, into which space the protuberances made by punching project inwardly from the outer wall and outwardly from the inner 55 wall, and imperforate protuberances on one of said walls projecting into said annular space to gage the clearance of the water-inlet ways, substantially as specified.

In testimony whereof I have signed my 60 name to this specification in the presence of two subscribing witnesses.

ANDREW SMITH.
